[57] CLAIM

The ornamental design for a camera, substantially as shown and described.

DESCRIPTION

FIG. 1 is a top and right-front perspective view of a camera showing my new design, with the cover-handle in the open position and the flash extended; FIG. 2 is a top and right-front perspective view thereof, with the flash retracted and the cover-handle in the closed position;

FIG. 3 is a rear elevational view of FIG. 2;

FIG. 4 is a left side elevational view of FIG. 2;

FIG. 5 is a top plan view of FIG. 2;

FIG. 6 is a bottom plan view of FIG. 2;

FIG. 7 is a bottom plan view of FIG. 1 but with the flash retracted.

FIG. 1

FIG. 2
